Primary Examiner — Lakiya Rogers*Assistant Examiner* — Harold Blackwell, II(57) **CLAIM**

The ornamental design for a hexkey holder, as shown and described.

DESCRIPTION

FIG. 1 is a perspective view of a hexkey holder showing my new design;

FIG. 2 is a front side view thereof;

FIG. 3 is a back side view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof with hexkey.

The broken lines in FIGS. 7 and 8 illustrate the environment of the claimed design and forms no part of the claimed design.
